(57) **CLAIM**

The ornamental design for a nasal cannula assembly, as shown and described.

DESCRIPTION

FIG. 1 is top, front right perspective view of a nasal cannula assembly.

FIG. 2 is a top, rear left perspective view of the nasal cannula assembly of FIG. 1.

FIG. 3 is a bottom, front right perspective view of the nasal cannula assembly of FIG. 1.

FIG. 4 is a bottom, rear left perspective view of the nasal cannula assembly of FIG. 1.

FIG. 5 is a rear view of the nasal cannula assembly of FIG. 1.

FIG. 6 is a front view of the nasal cannula assembly of FIG. 1.

FIG. 7 is a bottom view of the nasal cannula assembly of FIG. 1.

FIG. 8 is a top view of the nasal cannula assembly of FIG. 1.

FIG. 9 is a right side view of the nasal cannula assembly of FIG. 1.

FIG. 10 is a left side view of the nasal cannula assembly of FIG. 1.

FIG. 11 is an enlarged top, rear left perspective view of a nasal cannula component of the nasal cannula assembly of FIG. 1.

(Continued)

FIG. 12 is an enlarged bottom, rear left perspective view of the nasal cannula component of FIG. 11.

FIG. 13 is an enlarged top, front right perspective view of the nasal cannula component of FIG. 11.

FIG. 14 is an enlarged bottom, front right perspective view of the nasal cannula component of FIG. 11.

FIG. 15 is an enlarged rear view of the nasal cannula component of FIG. 11.

FIG. 16 is an enlarged front view of the nasal cannula component of FIG. 11.

FIG. 17 is an enlarged bottom view of the nasal cannula component of FIG. 11.

FIG. 18 is an enlarged top view of the nasal cannula component of FIG. 11.

FIG. 19 is an enlarged right side view of the nasal cannula component of FIG. 11.

FIG. 20 is an enlarged left side view of the nasal cannula component of FIG. 11.

FIG. 21 is a bottom, right perspective view of a tube subassembly component of the nasal cannula assembly of FIG. 1.

FIG. 22 is a top, right perspective view of the tube subassembly component of FIG. 21.

FIG. 23 is a right end perspective view of the tube subassembly component of FIG. 21.

FIG. 24 is a left end perspective view of the tube subassembly component of FIG. 21.

FIG. 25 is a bottom view of the tube subassembly component of FIG. 21.

FIG. 26 is a top view of the tube subassembly component of FIG. 21.

FIG. 27 is a rear view of the tube subassembly component of FIG. 21.

FIG. 28 is a front view of the tube subassembly component of FIG. 21.

FIG. 29 is an enlarged top, rear left perspective view of an elbow connector component of the tube subassembly of FIG. 21.

FIG. 30 is an enlarged top, rear right perspective view of an elbow connector component of the tube subassembly of FIG. 21.

FIG. 31 is an enlarged bottom, front right perspective view of an elbow connector component of the tube subassembly of FIG. 21.

FIG. 32 is an enlarged bottom, rear right perspective view of an elbow connector component of the tube subassembly of FIG. 21.

FIG. 33 is an enlarged front right perspective view of an elbow connector component of the tube subassembly of FIG. 21.

FIG. 34 is an enlarged rear left perspective view of an elbow connector component of the tube subassembly of FIG. 21.

FIG. 35 is an enlarged top view of an elbow connector component of the tube subassembly of FIG. 21.

FIG. 36 is an enlarged bottom view of an elbow connector component of the tube assembly of FIG. 21.

FIG. 37 is an enlarged right end view of an elbow connector component of the tube subassembly of FIG. 21.

FIG. 38 is an enlarged left end view of an elbow connector component of the tube subassembly of FIG. 21.

FIG. 39 is an enlarged top perspective view of a clip component of the nasal cannula assembly of FIG. 1 and is shown in an open configuration.

FIG. 40 is an enlarged top perspective view of the clip component of FIG. 39 shown in an open configuration.

FIG. 41 is an enlarged bottom perspective view of the clip component of FIG. 39 shown in an open configuration.

FIG. 42 is an enlarged bottom perspective view of the clip component of FIG. 39 shown in an open configuration.

FIG. 43 is an enlarged right side view of the clip component of FIG. 39 shown in an open configuration.

FIG. 44 is an enlarged left side view of the clip component of FIG. 39 shown in an open configuration.

FIG. 45 is an enlarged bottom view of the clip component of FIG. 39 shown in an open configuration.

FIG. 46 is an enlarged top view of the clip component of FIG. 39 shown in an open configuration.

FIG. 47 is an enlarged rear view of the clip component of FIG. 39 shown in an open configuration.

FIG. 48 is an enlarged front view of the clip component of FIG. 39 shown in an open configuration.

FIG. 49 is an enlarged top perspective view of the clip component of FIG. 39 shown in a closed configuration.

FIG. 50 is an enlarged bottom perspective view of the clip component of FIG. 39 shown in a closed configuration.

FIG. 51 is an enlarged top, front right perspective view of a facemount component of the nasal cannula assembly of FIG. 1.

FIG. 52 is an enlarged top, rear perspective view of the facemount component of FIG. 51.

FIG. 53 is an enlarged rear, left perspective view of the facemount component of FIG. 51.

FIG. 54 is an enlarged bottom, right perspective view of the facemount component of FIG. 51.

FIG. 55 is an enlarged rear view of the facemount component of FIG. 51.

FIG. 56 is an enlarged front view of the facemount component of FIG. 51.

FIG. 57 is an enlarged bottom view of the facemount component of FIG. 51.

FIG. 58 is an enlarged top view of the facemount component of FIG. 51.

FIG. 59 is an enlarged right side view of the facemount component of FIG. 51.

FIG. 60 is an enlarged left side view of the facemount component of FIG. 51.

FIG. 61 is an enlarged top, front right perspective view of the combination of nasal cannula and facemount components of the nasal cannula assembly of FIG. 1.

FIG. 62 is an enlarged bottom, front right perspective view of the combination of nasal cannula and facemount components of FIG. 61.

FIG. 63 is an enlarged rear left perspective view of the combination of nasal cannula and facemount components of FIG. 61.

FIG. 64 is an enlarged top, rear left perspective view of the combination of nasal cannula and facemount components of FIG. 61.

FIG. 65 is an enlarged rear view of the combination of nasal cannula and facemount components of FIG. 61.

FIG. 66 is an enlarged front view of the combination of nasal cannula and facemount components of FIG. 61.

FIG. 67 is an enlarged bottom view of the combination of nasal cannula and facemount components of FIG. 61.

FIG. 68 is an enlarged top view of the combination of nasal cannula and facemount components of FIG. 61.

FIG. 69 is an enlarged left side view of the combination of nasal cannula and facemount components of FIG. 61; and,

FIG. 70 is an enlarged right side view of the combination of nasal cannula and facemount components of FIG. 61. The broken lines in the drawings depict portions of the nasal cannula assembly that form no part of the claimed design.
